UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION.

DIE HEAD.

Application filed May 21, 1926. Serial No. 110,789.

Fig. 1 is a view in side elevation of a die-head embodying my invention;

Fig. 2 is a view thereof in transverse section on the line 2—2 of Fig. 1;

5 Fig. 3 is a broken sectional view on the line 3—3 of Fig. 2;

Fig. 4 is a similar view on the line 4—4 of Fig. 2;

10 Fig. 5 is a view of the die-head in central longitudinal section, showing the fixture as closed, preparatory to a threading operation;

Fig. 6 is a corresponding view, showing the parts in the positions due to them at the conclusion of a threading operation and at 15 the instant of the disengagement of the locking-segment from the operating-sleeve and before the same has been moved rearward, which will instantly follow;

Fig. 7 is a detached view in rear elevation of 20 the tripping-sleeve;

Fig. 8 is a corresponding view of the operating-sleeve; and

25 Fig. 9 is a detached perspective view of a modified form of my intermediate or transmission trip-member.

My invention relates to an improvement in self-opening die-heads, the object being to produce a simple, effective and durable fixture constructed with particular reference to 30 its provision with sensitive and therefore responsive means for tripping it.

With these ends in view, my invention consists in a self-opening die-head characterized by having a rotary, bodily-movable transmission-member interposed between its locking-member and its tripping-sleeve.

My invention further consists in a die-head characterized as above and having certain other details of construction as will be hereinafter described and pointed out in the claims.

In carrying out my invention, as herein shown, I employ an intermediate or transmission trip-member 10 in the form of a ball having bodily and rotary movement in a radial passage 11 formed in the rear portion of an operating-sleeve 12 having rectilinear movement upon a skeleton die-head body 13. The said ball projects outwardly into a shallow 45 notch 14 having an inclined forward wall 15 and leading out of the inner periphery of the rear end of a tripping-sleeve 16 having rectilinear movement upon the operating-sleeve 12 aforesaid. The rear end of the said sleeve 50 16 is provided with an annular groove 17 de-

signed to receive a yoke or other suitable abutment properly located in the machine in which the die-head is used in the ordinary manner, and not shown herein. The said ball 10 rides upon and co-acts directly with the periphery 60 of a radially-movable locking-segment 18 located in a circumferential groove 19 in the adjusting-ring 20 of the die-head, the said ring being internally threaded, as usual, for being screwed upon the threaded portion of 65 the tubular shank 21 of the die-head body 13. Diametrically opposite the locking-segment 18 and in the same groove 19, I locate a stationary complementary filler-segment 23 having neither radial nor endwise movement, and 70 formed in its ends with notches 24 receiving helical springs 25 respectively abutting against the ends of the locking-segment 18 and exerting a constant effort to move the same radially outward for the engagement of 75 its forward outer edge 26 with an abutment-shoulder 27 formed by the forward wall of an eccentric groove 28 leading out of the inner periphery of the operating-sleeve 12.

To prevent the relative rotation of the operating-sleeve 12 and the die-head body 13, the said sleeve is provided at opposite points in its forward face with two guide-pins 29 entering corresponding holes 30 in the body 13, the said pins reciprocating back and forth in 80 the holes as the sleeve is moved back and forth in the operation of the fixture.

For the self-opening action of the die-head, I employ two helical springs 31 (Figs. 2 and 4) located opposite each other and extending at their opposite ends into deep bores 32 in the operating-sleeve 12 and into complementary bores 33 in the body 13.

As herein shown, my improved die-head is provided with radially-movable chasers 34 respectively located in radial grooves 35 in the forward face of the body 13. Spring-actuated plungers 36 exert a constant effort to move the chasers outward, so that their beveled outer ends 37 will engage with bevels 38 in the 95 inner edge of the outer end of the operating-sleeve 12 (Figs. 5 and 6). But the specific character of the chasers and the mode of mounting and operating them has nothing to do with my present invention, since so far 100 as my improved tripping-mechanism is concerned, it may be used in self-opening die-heads furnished with chasers of different construction, mode of mounting and operation.

As shown in Figs. 1 to 5 inclusive, my im- 110

proved die-head is in its closed position, ready for a threading operation, at which time the locking-segment 18 is pushed outward into the eccentric groove 28 in the sleeve 12 in which position its forward edge 26 co-acts with the abutment-shoulder 27 formed by the forward wall of the groove 28, whereby the sleeve is locked in its forward position against the counter-urge of the springs 31. In this 10 position of the segment 18, it holds the chasers 34 in their cutting positions against the tension of their spring-actuated plungers 36, and the sleeve 12 against the counter-urge of the helical springs 31, the said plungers tending 15 to move the chasers outward and the said springs tending to move the said sleeve rearward. At this time, also, the tripping-sleeve 16 is at the limit of its forward movement, as shown in Fig. 5.

20 At a predetermined point in the threading operation, during which the die-head is moved toward the work, the tripping-sleeve 16 is arrested by the yoke or other suitable abutment set in the usual and well-known manner according to the character of the work to be done, in the machine in which the die-head is being used. When the tripping-sleeve is thus arrested, the ball 10 being carried forward with the die-head is forced inward by its engagement with the inclined forward wall 15 of the notch 14 in the tripping-sleeve 16 now at a standstill, with the effect of transmitting its bodily inward movement to the locking-segment 18, which in turn is forced radially 25 inward, so as to disengage its forward outer edge 26 from the abutment-shoulder 27, as shown in Fig. 6. The springs 31 now assert themselves to move the operating-sleeve 12 rearwardly with respect to the body 13, so as 30 to permit the chasers 34 to be moved radially outward, away from the work, by their spring-actuated plungers 36. It is to be noted in this connection that when the ball 10 is being moved radially inward, it is free to have 35 rotary as well as bodily movement, resulting

in an exceedingly sensitive and responsive action between its tripping-sleeve 16 and the locking-segment 18 or whatever else may take the place thereof, there being no opportunity for cramping or undue wear.

Instead of using a transmission-member in the form of a ball 10, I might substitute therefor a roller 39, as shown in Fig. 9, arranged to have rotary as well as bodily movement.

I claim:

1. A self-opening die-head having a body, chasers, an operating-sleeve therefor having a radial passage, a locking-member for holding the said operating-sleeve in position for maintaining the chasers in their cutting positions, a tripping-sleeve mounted upon and axially movable over the said operating-sleeve so as to entirely overlie the said radial passage therein, and a transmission-member interposed between the said locking-member and tripping-sleeve, having bodily and rotary movement in the said radial passage in the operating-sleeve, and being at all times confined in the said passage and covered by the overlying tripping-sleeve.

2. A self-opening die-head having a body, chasers, an operating-sleeve therefor having a radial passage, a locking-member for holding the said operating-sleeve in position for maintaining the chasers in their cutting positions, a tripping-sleeve mounted for axial movement upon the said operating-sleeve so as to entirely overlie the said radial passage therein and having its inner periphery formed with a recess having a forward wall adjacent to the said passage in the operating-sleeve, and a rotary and bodily-movable ball interposed between the said locking-member and tripping-sleeve and located in the said radial passage and coacting with the inclined wall of the recess in the tripping-sleeve which at all times overlies and confines it.

In testimony whereof I have signed this specification.

ALBERT F. BREITENSTEIN.
